UNITED STATES PATENT OFFICE.

JOHN E. CHALMAN, OF CHICAGO, ILLINOIS, ASSIGNOR TO UNION SPECIAL MACHINE COMPANY, OF CHICAGO, ILLINOIS, A CORPORATION OF ILLINOIS.

FOLDING AND GUIDING ATTACHMENT FOR SEWING-MACHINES.

1,214,133.

Specification of Letters Patent. Patented Jan. 30, 1917.

Application filed February 9, 1912. Serial No. 376,536.

To all whom it may concern:

Be it known that I, JOHN E. CHALMAN, a citizen of the United States, residing at Chicago, in the county of Cook, State of Illinois, have invented certain new and useful Improvements in Folding and Guiding Attachments for Sewing-Machines, of which the following is a description, reference being had to the accompanying drawing and to the figures of reference marked thereon.

My invention relates to folding guides for attachment to sewing machines, the object being to provide such an attachment to guide and turn a hem on a piece of fabric, and at the same time fold around the edge of the hem fold a binding strip, to deliver the same to the stitch-forming mechanism of a sewing machine, whereby the fabric, the turned-in portion thereof and the binding strip hem folds are secured together by a line of stitching.

The invention is illustrated in the accompanying drawings, in which,—

Figure 1 is a front view in perspective 25 of a folder constructed in accordance with my invention, the presser foot and a portion of the stitch-forming mechanism being indicated; Fig. 2 is a view of the folder looking from the front; Fig. 3 is a similar view 30 looking from the rear; Fig. 4 is a cross section; and Fig. 5 is a cross section of the seam formed by the use of my folder in connection with stitch-forming mechanism.

In these drawings, 1 represents a base 35 piece adapted to be adjustably attached to the bed plate of a sewing machine. The sewing machine herein shown, or so much as is necessary to a complete understanding of my invention, is of the well known Union 40 Special type of two-line machine.

Extending from the base piece is a vertical wall 2 having a substantially horizontally extending lip 3, which overhangs a portion of the plane surface 4 upon which the main fabric rests. Beneath the inner edge of the surface 4 is a recess 5, which forms with the lip 3, the edge 6 and the inner face of the vertical wall 2 a folding and guiding recess to form a hem fold on the main piece of fabric. Attached to or formed with the body part of the folder is the vertically curved and tapering guide 7 for the binding strip, the inner concave wall of which at its forward end is cut away as at 8, so that the raw 55 edge of the hem fold may be in contact with

the binding strip. The binding strip guide is tapered and curved so as to embrace the raw edge of the hem fold, and the walls are turned in, so as to form hem folds on the upper and lower faces of the binding strip.

Attached to the under side of the surface 4 is the wire 9, forming a loop 10 to guide the binding strip to the opening of the binding guide 7.

Projecting rearwardly from the vertical wall 2 and wall of the binding guide, are vertical walls 15, chamfered off to come under the toe of the presser foot, and by these walls the edge of the fabric and the bound edge of the hem fold are kept in proper relation and guided to the stitch-forming mechanism.

In operation, the fabric is inserted in the folder from the left on top of the plane surface, and forms the hem fold 12, as shown in Fig. 3. The binding strip is guided through the loop 10 into the binding guide 7. As the parts are fed to the stitch-forming mechanism, a line of stitching 13 passes down through the fabric, the upper fold of the binding strip, the hem fold of the fabric and the lower fold of the binding strip, and if desired to increase the ornamental appearance of the fabric, a line of stitching 14 passes through the edge of the fabric and the hem fold.

Having thus described my invention, what I claim as new and desire to secure by Letters Patent, is:—

1. A folding guide for sewing machines comprising a supporting base, a fabric support projecting laterally from said base and terminating in a guiding recess, whereby the edge of the fabric is folded back upon itself, said folding guide having a recess extending above and below the end of said first named recess for guiding a tape, said recesses merging into each other at the delivery end of the folder, whereby the tape is folded around the edge of the folded back fabric.

2. A folding guide for sewing machines comprising a supporting base, a fabric support projecting laterally from said base and terminating in a guiding recess, whereby the edge of the fabric is folded back upon itself, said folding guide having a recess extending above and below the end of said first named recess for guiding a tape, said recesses merging into each other at the de-

- livery end of the folder, whereby the tape is folded around the edge of the folded back fabric, said recess for the tape having means for folding the edges of the tape as it passes through the folder.
3. A folding guide for sewing machines comprising a supporting base, a vertical wall rising therefrom and having a laterally projecting lip, a fabric support carried by said base and extending laterally therefrom and beneath said lip, said fabric support being spaced from said lip and vertical wall, and from said supporting base at its inner side, whereby a fabric resting on said support may be folded back underneath itself, said supporting base and fabric support having a guiding recess formed there-through extending above and below the edge of the folded fabric, whereby a tape may be folded around the edge of the fabric.
4. The combination of a sewing machine having spaced needles of a folding guide

comprising a supporting base, a fabric support projecting laterally from said base and terminating in a guiding recess whereby the edge of the fabric is folded back upon itself, said folding guide having a recess extending above and below the end of said first named recess for guiding a tape, said recesses merging into each other at the delivery end of the folding guide whereby the tape is folded around the edge of the folded back fabric, said folding guide being so disposed relative to said spaced needles that one of said needles passes through the folded fabric adjacent the fold therein while the other needle passes through the fabric adjacent the free edge of the fold and through the edges of said tape.

In testimony whereof, I affix my signature in the presence of two witnesses.

JOHN E. CHALMAN.

Witnesses:

C. McNEIL,
M. A. ALLEN.
